UNITED STATES PATENT OFFICE.

CALVIN DEAN, OF PROVIDENCE, RHODE ISLAND.

DESIGN FOR A PROTECTOR FOR ARTICLES TO BE WORN ON THE WRIST.

51,225.

Specification for Design.

Patented Sept. 4, 1917.

Application filed July 18, 1917. Serial No. 181,421. Term of patent 7 years.

To all whom it may concern:

Be it known that I, CALVIN DEAN, a citizen of the United States, residing at Providence, in the county of Providence and State of Rhode Island, have invented a certain new, original, and ornamental Design for a Protector for Articles to be Worn on the Wrist, of which the following is a specification.

In the accompanying drawings which form a part of this specification the figure is a plan of a protector for use with wristlet watches and similar articles to be worn on the wrist and showing my new design.

I claim—

The ornamental design for a protector for articles to be worn on the wrist, as shown.

CALVIN DEAN.
